UNITED STATES PATENT OFFICE.

JAMES B. LADD, OF ARDMORE, PENNSYLVANIA.

HAIR-PIN.

1,137,147.

Specification of Letters Patent. Patented Apr. 27, 1915.

Application filed November 27, 1911. Serial No. 662,557.

To all whom it may concern:

Be it known that I, JAMES B. LADD, a citizen of the United States, residing at Ardmore, in the county of Montgomery, State of Pennsylvania, have invented a new and useful Hair-Pin, of which the following is a specification.

My invention relates to improvements in hair pins.

10 The object is to provide improved means whereby, in manipulating the device, the free ends of the prongs will be made to change their relative positions before or while inserting the device in the hair and upon releasing the same said free ends will tend to assume the initial position to firmly 15 clamp or embrace the hair engaged between the prongs.

20 Referring to the drawings illustrating, merely by way of example, suitable means for effecting my invention Figure 1 is a perspective view of one side of the hair pin. Fig. 2 is a perspective view of the other side of the hair pin. Fig. 3 is a perspective view of the hair pin held in the hand and pressed between the fingers so as to cause a displacement or a change in the relative 25 positions of the free ends of the prongs.

20 I have shown merely by way of example a hair pin containing three prongs. The two outer prongs 4 and 5 are shown straight from the upper connecting ends of said prongs, which we will call the head, while the middle prong 6 is provided with a bend 35 7 out of the plane in which the other two prongs and the balance of prong 6 normally lie. The connecting ends of the prongs are

substantially fixed or immovable with respect to one another, but resiliently related as to their free ends.

40 By referring to Fig. 3, it will be seen that when the device is taken between the thumb and finger and pressure exerted on the hump or bend 7 by the thumb and the opposite side of adjacent prongs, the lower end of 45 prong 6 is thrown considerable out of the plane in which prongs 4 and 5 remain. By then inserting the device in the hair and releasing the same, prong 6 tends to return, 50 by reason of its resilience, to its initial position thereby clamping the hair which is interposed between prong 6 and prongs 4 and 5, thus the hair pin is firmly held in place until again manipulated.

55 What I claim is:

A hair pin having more than two prongs with a common fixed point of connection whereby they are relatively immovable with respect to one another at said point, said prongs beyond said point being resiliently 60 related, but normally lying in a common plane, including in its number a prong having a hump or extension projecting out of said common plane and adjacent the head, said hump or extension provided for the 65 purpose of throwing a prong out of said common plane by exerting pressure on said hump and the opposite sides of adjacent prongs, as and for the purpose specified.

JAMES B. LADD.
